Primary Examiner—Gary D. Watson*Assistant Examiner*—T. Chase Nelson(74) *Attorney, Agent, or Firm*—The Eclipse Group LLP(57) **CLAIM**

The ornamental design for a surface pattern for leather goods, as shown and described.

DESCRIPTION

FIG. 1 is an enlarged perspective view of the front side of the surface pattern for leather goods;

FIG. 2 is a perspective view of the front side of the surface pattern for leather goods shown at actual size;

FIG. 3 is a front plan view of the surface pattern for leather goods;

FIG. 4 is an elevation view of the bottom edge of the surface pattern for leather goods; and,

FIG. 5 is a rear plan view of the surface pattern for leather goods.
